UNITED STATES PATENT OFFICE.

ELMER A. SPERRY, OF BROOKLYN, NEW YORK.

ELECTRIC-ARC LIGHT.

1,302,488.

Specification of Letters Patent. Patented Apr. 29, 1919.

Application filed November 11, 1914. Serial No. 871,436.

To all whom it may concern:

Be it known that I, ELMER A. SPERRY, a citizen of the United States of America, residing at 100 Marlborough road, Brooklyn, 5 New York, have invented certain new and useful Improvements in Electric-Arc Lights, of which the following is a specification.

This invention relates to arc lights and has for its object to provide novel means for rotating, feeding, and supplying current to an electrode of a searchlight.

The apparatus used in carrying my invention into effect may necessarily assume a variety of forms. The form as applied to 15 searchlights which is now considered to be preferable is illustrated more or less diagrammatically in the accompanying drawings, in which

Figure 1 is a view of the positive electrode holder, with the electrode in place.

Fig. 2 is a longitudinal section of the same.

Referring more in detail to the drawings, 1 represents an electrode, the axially extending aperture of which is shown at 2. The 25 normal form of crater formed in actual operation is roughly shown at 2'. To provide for the unusual operating conditions of my light, I have devised a novel form of electrode holder, designed both to feed the carbon through the holder and to rotate it. Adjacent one end, the holder is provided with a rotatably mounted bevel gear 3, journaled on an extension 4 of the main body 5 of the holder. Said gear 3 is rotated by a bevel 35 pinion 6, journaled in fixed bearings within and without the arc lamp and rotated from any suitable source of power, represented by belt 7, at the desired speed. Pivottally mounted on the face of said bevel gear are a pair 40 of brackets 8 and 9 which are normally pulled toward each other by springs 10. These brackets carry feed rollers 11 and 12 for the carbon, the former being knurled or provided with teeth, while the latter is made 45 in the form of a pair of separated disks 13 and 14, thus providing a three-point support for the carbon. The rollers are rotated by means of a worm wheel 15, mounted on the shaft of roller 12, and receiving its motion 50 from worm 16. Motion may be transmitted to roller 11 through gears 17 and 18, mounted on the shafts of rollers 11 and 12, respectively. The worm is journaled on extensions from bracket 9, and is provided with a star 55 wheel 19, designed to engage an adjustable stop 20. Said stop may be mounted adja-

cent pinion 6, and is preferably arranged to be automatically controlled by the relative position of the arc light carbons. This may be accomplished by means of a solenoid 21, 60 operated to withdraw the stop against the action of a spring 22, when the carbons approach each other too closely, as will be readily understood by those skilled in the art.

The main body 5 of the holder is preferably corrugated as shown, to aid in the dissipation of heat. A plurality of spring pressed silver brushes 23 are provided to carry the main portion of the current into the carbon, with which they have sliding 70 contact. A silver insert 24 may be provided opposite brushes 23 to keep the contacting surfaces in good condition. The holder is preferably also provided with an extension 25 of some highly refractory material, such 75 as fire brick, alundum, nickel-steel, etc., designed to extend close to the arc itself and prevent the arc spreading back on the outside of the carbon. This extension or cap 25 may be removably secured to the face of the 80 holder as by means of bolts 25'.

The mechanical operation of the structure shown upon the drawings is as follows:

Firstly, let it be understood that no attempt has been made to illustrate a complete searchlight mechanism, no negative carbon or feeding mechanism therefore being shown. For feeding the positive carbon I have illustrated a special holder, designed to feed the carbon through the 90 holder, so that very long carbon sticks may be employed. As the bevel gear 6, which forms in effect a base piece, is revolved it rotates the carbon 1 with it, through the gripping action of the spring pressed rollers 95 11 and 12. Gear 6 also carries with it the star wheel 19, which strikes stop 20 once each revolution and is rotated thereby so as to rotate the feed rollers on their own axes. The carbon is thus moved slowly forward, 100 the rate of feeding being governed by the automatic adjustment of the position of stop 20, as explained above. Thus the feed rollers perform the double function of both rotating and feeding the carbon.

In accordance with the provisions of the patent statutes, I have herein described the principle of operation of my invention, together with the apparatus which I now consider to represent the best embodiments 110 thereof, but I desire to have it understood that the apparatus shown is only illustra-

tive and that the invention can be carried out by other means. Also, while it is designed to use the various features and elements in the combination and relations described some of these may be altered and others omitted without interfering with the more general results outlined, and the invention extends to such use.

Having now described my invention, what 10 I claim and desire to secure by Letters Patent is:

1. In an arc lamp, an electrode holder comprising a base piece revolvably mounted concentrically with the electrode, a feed 15 roller rotatably mounted on said base, means to rotate both the base and the roller on their respective axes, whereby the said roller transmits both a rotary and a translatory motion to the electrode, and means comprising a spring pressed brush for conveying electric current to the electrode and for imposing a frictional resistance to movement of the electrode through said holder.

2. An electrode holder for searchlights 25 comprising a body portion having an electrode receiving bore, a rotatable member mounted on said body portion, means for rotating said member, feeding means mounted on said member, means regulated inde-

pendently from the rotation of said member 30 but operated thereby, for actuating said feeding means whereby a constant rotation and regulatable feed of the electrode is secured, and a spring pressed current-conveying brush biased to a position in which it 35 extends into said bore.

3. An electrode holder for searchlights comprising a body portion having an electrode-receiving bore, a rotatable member mounted on said body portion, means for 40 rotating said member, feeding means mounted on said member, a star wheel mounted on said member and connected to said means, a stop normally in the path of said wheel, means responsive to the position of the electrode for governing the position of said stop, and means comprising a spring pressed brush for pressing the electrode laterally against said holder.

In testimony whereof, I have signed my 50 name to this specification in the presence of two subscribing witnesses, this 30th day of October, 1914.

ELMER A. SPERRY.
